VENETIAN BLIND

Charles Adler, Cincinnati, Ohio

Application August 6, 1945, Serial No. 609,069

5 Claims. (Cl. 160—166)

1

This invention relates to improvements in Venetian blinds and particularly to improvements in appurtenances therefore.

Venetian blinds, per se, are quite old but difficulty has been experienced in properly cleaning the so-called "slats" of the blind and in changing or substituting the slats' supporting means generally referred to as tapes and referred to in the trade as "ladder tapes." By this invention the foregoing difficulties are obviated resulting in a mechanism more conveniently operated and taken care of.

It is therefore an object of this invention to provide in a Venetian blind improved means for changing the supporting tapes.

It is also an object of this invention to provide means whereby the surfaces of the Venetian blind slats may be more expeditiously cleaned.

Another object of this invention is the provision of a tape or particularly a ladder tape that can be removed from the blind and placed thereon without completely disassembling the same, that is, removing it from its support, removing the ropes that effect the raising and lowering of the slats, or otherwise dismantling the blind.

It is also an object of this invention to provide means for retaining the blind slats in their proper and relative positions during the cleaning thereof while permitting the removal of the tapes so that they do not interfere with the slats' cleaning and whereby new or renovated tapes may be substituted for those removed.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is an elevational view of a Venetian blind embodying the improvements of this invention.

Fig. 2 is a vertical sectional view taken on line 2—2 on Fig. 1.

Fig. 3 is a vertical sectional view taken through a plane to the right of that of Fig. 2 on line 3—3 of Fig. 1.

Fig. 4 is a fragmentary perspective view of a portion of the improved ladder tape of this invention.

Fig. 5 is an enlarged fragmentary perspective

2

view of the means which retain the slats in their proper and relative position during the cleaning thereof and the substitution of supporting tape.

Fig. 6 is an enlarged plan view of a portion of the blind as seen from line 6—6 on Fig. 1.

Fig. 7 is a sectional view taken on line 7—7 on Fig. 6.

Fig. 8 is an enlarged fragmentary sectional view taken on line 8—8 on Fig. 1.

Fig. 9 is an enlarged fragmentary sectional view taken on line 9—9 on Fig. 1.

Throughout the several views of the drawing similar reference characters are employed to denote the same or similar parts.

15 The Venetian blind of this invention comprises, as usual, a head board 10 secured by brackets 11 and 12 in the opening of a window, door, or the like, and which opening is indicated by framing 13.

20 Connected to the head board 10 is the tilt board 14 mounted in place by suitable brackets 15 and 16 depending from the head board 10. The brackets 15 and 16 connect the tilt board in such manner that it may be oscillated about, substantially, its longitudinal axis through a suitable tilting mechanism indicated in general by the reference numeral 17. Ropes or other flexible members 18 are employed for actuating the tilt mechanism 17 and thereby tilting or oscillating the tilt board 14 all as is usual practice.

25 Spaced below the tilt board 14 are the slats 19 the number of which depends upon the area to be covered thereby and the width of the individual slats since fewer slats would be required if the individual slats were wider than would be necessary with narrower individual slats. Below the lowermost slat 19 is a rail 20 and the rail is considerably heavier than the slats so that weight is given to the blind as a whole for the purpose of extending the slats for the length of the opening. The individual slats and rail 20 are held in spaced-apart relation from and below the tilt board 14 by flexible members or tapes 21 and 22. These tapes 21 and 22 have their upper ends secured to the tilt board 14 and their lower ends secured to the board rail 20. As is well known the tapes 21 and 22 have a length on each side of the blind and are connected to one another by crossing members simulating the steps of a ladder wherefore the trade name or designation "ladder tape."

30 In order to remove the slats from the opening, that is completely uncover the opening, the various slats are adapted to be brought into surface contact with one another, with the upper surface of each slat in

contact with the lower surface of the next slat there above and with the upper surface of the bottom rail 20 engaging the lower surface of the lowermost slat. In order to do this use is made of a rope or ropes which extend longitudinally of the tilt board 14 on its upper surface or preferably within a channel 23 let into the upper surface of the tilt board and which rope or ropes 24 and 25 respectively pass between the front and the back layers of tapes 22 and 21. The ropes 24 and 25 pass beyond one end of the tilt board 14 to the inside of the Venetian blind and depend to a point within reach of the operator and the said ropes are frequently joined as indicated at 26 wherefore they are actuated together to raise and lower both sides of the Venetian blind slats equally and simultaneously.

Each of the slats 19 is provided with a transverse elongated aperture 27 shown in phantom lines in Fig. 4 wherefore the said slats may be tilted or oscillated about their longitudinal axes without binding on the ropes which pass therethrough. In the past the transverse members or "ladder steps" alternated one on each side of the rope wherefore the rope had to be threaded through the slats and between the tape transverse members, a time consuming and laborious task.

Substantially all of the foregoing description is that of Venetian blinds as heretofore employed together with its attendant objections which by the present invention has been eliminated.

Since each of the tapes 21 and 22 are substantially identical it is deemed sufficient that a disclosure of one will suffice for the other. Accordingly, tape 21, for example as illustrated in Figs. 4, 6, 7 and 8, comprises a tape length 28 adapted to extend along the outer side of the Venetian blind as viewed from the operator's side thereof and a second length of tape 29 along the inner side of said line. The said tapes 28 and 29 are secured to one another by transverse members or ladder steps 30 having one end 31 secured to the tape 28 as for example by steps 32 and the transverse member 30 has its other end 33 secured to the tape length 29 by any suitable means such for example as steps 34. This connection of the ends 31 and 33 with the tapes 28 and 29 may take any other form such, for example, as that referred to in the trade as "loose thread." The distinction of the present ladder tape from those heretofore employed is that the transverse members or ladder steps 30 are substantially all on one side or along the same opposite edges of the tape lengths 28 and 29 instead of the said transverse members alternating as they ascend or descend the length of said tape lengths 28 and 29.

At relatively widely spaced intervals the other sides or edges of the tape lengths 28 and 29 are connected by transverse members 35. As shown in Fig. 1 use is made of but three of said transverse members 35 as against twenty-four transverse members 30. The transverse members 35 each have one end 36 permanently secured to one of the tapes 29 in a manner similar to the securing of each end of the transverse members 30, for example by stitches 37, or any other suitable or desirable means. The other end 38 of the transverse member 35 is only removably secured to the tape length 28 and any suitable or desirable means for accomplishing this may be employed. As shown in Fig. 8, the means illustrated in the drawings is in the form of a dress snap fastener including the male member 39 permanently secured to the tape 29 and the female

member 40 carried by the end 38 of the transverse member or ladder step 35.

From the foregoing it will be seen that by un-snapping one of the ends of each of the few transverse members 35 from the tape 29 the tape unit 21 may be slid off the ends of the individual slats 19.

In order to do this it is necessary that the slats 19 be held in spaced-apart relation to one another and in substantially the same relation that they maintain relative to the opening with which they are employed. This is accomplished by the use of a relatively rigid member such as a stick or bar 41 having projecting from one face thereof a plurality of pins, pegs, or fingers 42 spaced from one another longitudinally of the bar the same distance that the slats 19 are spaced. Each of the members 42 is provided at its free end with a head or flange 43 for a purpose later to be made clear. The bar 41 is adapted to be hung from a fixed position of the Venetian blind for example the head board 10. For this purpose the bar 41 is provided with an aperture 44 through which extends the shank 45 of a hook 46. The shank 45, as seen in Fig. 3, is of considerable length to extend beyond the Venetian blind and particularly the head board 10.

In practice the hook 46 of the bar support bracket is engaged with the rear edge of the head board 10 and the bar 41 arranged adjacent the inner edge of the slats 19 when they are in their horizontal position. This causes the pins, fingers or the like 42 to be respectively disposed one beneath each of the slats 19 with their heads 43 engaging the outer edge of their respective slats. The rope clamp 47 is released, in fact it is generally not in engagement when the Venetian blind is fully extended, whereupon the bar 41 is shifted from its solid line position to the phantom line position in Fig. 3. To determine the latter position of the bar 41 the supporting bracket shank 45 is provided with a head 48 on its free end. The shifting of the bar 41 to the phantom line position, indicated in the drawing by the reference numeral 49, brings the slats inwardly of the opening and particularly its frame 13 wherefore the tape unit 21 may be removed.

The upper end of the tape unit 21 is normally securely attached to the tilt board 14 but to permit its ready displacement from the Venetian blind it must be removably attached and which attachment may be effected in any suitable or desirable manner. One means for permitting the ready detachment of the tapes 28 and 29 from the tilt board 14 may consist in furcating the upper ends of each of the tapes 28 and 29 thereby providing fingers 50 and 51 on the tape 28 and similar fingers 52 and 53 on the tape 29. The fingers have their inner surfaces spaced from one another to permit the raising and lowering ropes 24 and 25 to pass there between. Each of the fingers of each tape is provided with an aperture preferably reinforced as by a metal ring 54 each adapted to be mounted on the shank 55 of an upstanding peg or the like carried by the tilt board 14.

The lower ends of the tapes 28 and 29 likewise must be readily removable from the board rail 20 and any suitable or desirable means may be provided for this purpose such for example as illustrated in Fig. 9 which comprises a clip 56 having spring arms 57 and 58 at its ends respectively receivable in a socket 59 and 60 in the face edge of the board rail 20.

It is believed that the operation of the device

of this invention is obvious from the foregoing description but briefly is as follows:

The support bar 41 is suspended from a permanently mounted part of the Venetian blind such as the head board 10, with its fingers, pegs, or the like 42 beneath their respective slats 19 whereupon the support bar 41 and slats 19 are shifted to the position where they may be readily accessible. The release of the rope clamp 47 permits this shifting of the slats 19 relative to 10 the tilt bar. The fingers 50 to 53 are now released or were released previous to the outward shifting of the bar 41 and the clips 56 are likewise now removed thereby freeing the tape unit from the tilt bar 14 and bottom rail 20. The snap fastener or other releasable means of the several transverse members 35 are now opened whereupon the tape unit is removable endwise of the slats 19.

The slats, particularly at one side of the opening, may now be cleaned without interference by the tape unit and thereafter the tape unit replaced or substituted. In order to reposition a tape unit the reverse procedure from that above described is followed whereupon the bar 41 is removed from the blind or shifted to the other side thereof for replacing the unit 22.

It will be understood that if desired two support bars 41 may be employed, both tape units 21 and 22 replaced without shifting or otherwise moving the first bar 41.

From the foregoing it will now be appreciated that there has been provided an improved Venetian blind and particularly appurtenances therefore which accomplish the objects initially set forth.

What is claimed is:

1. A device of the class described for maintaining the slats of a Venetian blind in spaced parallel planes comprising a rigid member of a length equal to that of the Venetian blind when extended, a plurality of fingers projecting from the rigid member, one for each slat and adapted to underlie its slat, and an abutment at the end of each finger to prevent inadvertent separation of the fingers and their slats.

2. A device of the class described for maintaining the slats of a Venetian blind in spaced parallel planes comprising a rigid member of a length equal to that of the Venetian blind when ex- 50

tended, a plurality of fingers projecting from the rigid member, one for each slat and adapted to underlie its slat, and an abutment at the end of each finger to prevent inadvertent separation of the fingers and their slats, and means for movably mounting the rigid member for movement in the direction of extent of the axis of its fingers to correspondingly move said fingers and slats supported thereby.

3. A device of the class described for maintaining the slats of a Venetian blind in spaced parallel planes comprising a member of a length equal to that of the Venetian blind when extended, a plurality of fingers projecting from the member, one for each slat and adapted to underlie its slat and support it in position and means other than said fingers to support said member.

4. A device of the class described for maintaining the slats of a Venetian blind in spaced parallel planes comprising a solid member of a length equal to that of the Venetian blind when extended, a plurality of fingers inserted into and projecting from the member, one for each slat and adapted to underlie its slat, and an abutment at the end of each finger to prevent inadvertent separation of the fingers and their slats.

5. A device of the class described for maintaining the slats of a Venetian blind in spaced parallel planes comprising a rigid solid member of a length equal to that of the Venetian blind when extended, a plurality of fingers inserted into and projecting from the member, one for each slat and adapted to underlie its slat.
